UNITED STATES PATENT OFFICE

PAUL E. KUHL, OF ELIZABETH, NEW JERSEY, ASSIGNOR TO STANDARD OIL DEVELOPMENT COMPANY, A CORPORATION OF DELAWARE

APPARATUS FOR FRACTIONATING LIQUIDS

Application filed January 25, 1930. Serial No. 423,367.

This invention relates to improvements in fractionating equipment and particularly to means for controlling the side stream leaving the fractionating column.

5 In the operation of fractionating towers usually several side streams are taken out besides the overhead product and the bottoms. The side streams consist of hot liquid collected on one or several plates of a bubble tower, or in a pan, and are preferably passed through a stripping column before entering the final cooler. In this column the hot oil is brought into contact with a stripping agent, such as for instance superheated steam 10 which evaporates the light ends of the hot oil. The stripping agent and the vaporized light ends discharge into the fractionating column.

Control of the amount of distillate taken 20 out from the system of each side stream is essential since a change in this quantity affects the quality of all the heavier streams including the bottoms. It has been customary to control the stream withdrawn from 25 the main fractionating column by means of a valve in the hot liquid line between the fractionating and the stripping columns and then maintain the level in the bottom of the stripping column with a liquid level controller 30 which regulates the discharge from the stripping column. Such a control, however, is very inefficient because the position of the valve may be changed accidentally and the valve opening often becomes obstructed by 35 solid or gummy material carried in the stream.

The main object of the invention is to provide for the adjustment of a stable reflux in the fractionating column by controlling the 40 quantity of the side streams leaving the system through the stripping columns by means of a commercial rate of flow controller placed after the stripping column and then causing the liquid level control on the stripping column to operate a valve controlling the 45 amount of oil entering from the fractionating tower into the stripping column.

The invention will be fully understood 50 from the following description read in connection with the accompanying drawing, in

which the figure is a diagrammatic side elevation partly in section of preferred equipment.

In the drawing, the numeral 1 denotes a fractionating column such as for example a 55 bubble tower from which one or several side streams are taken out. 2 is the line for the hot feed entering the tower, 3 for the overhead vapors, 4 for bottoms, 5 for reflux. 6, 6', 6'' are the stripping columns, their number 60 being equal to the number of side streams. The further elements are identical on all side streams and will be shown only on one of them. 7 is a valved line for the superheated steam, 8 the line for the hot liquid taken out 65 from the tower and 9 for the returned vapors. The stripped liquid leaves the bottom of the stripping column through line 10 and cooler 11. A rate of flow controller 12 which may be of any approved type is installed in line 70 10 preferably after the cooler. Leads 13, 14 connect the rate of flow controller to both sides of the orifice plate 15. By a suitable actuating mechanism, well known in instruments of this type, the differential of the pressure 75 at both sides of the orifice plate 15 controls the flow of air which in turn closes the valve 16 through the lead 17 when the differential pressure reaches a certain fixed value. The flow in line 10 may be caused either by 80 gravity or by a pump 18. In the latter case controlled valve 16 in line 10 may be dispensed with and a controlled valve 19 placed in the steam line of the pump 18 as marked by dotted line. A certain portion of the 85 cooled stripped liquid may be returned through line 20 to provide reflux condensate. The pump or valve in this line may again be controlled by a rate of flow controller 21, the control of the reflux, however, does not 90 form part of this invention.

A liquid level control 22 is operatively connected with the outflow line 8 from the stripping column and actuates the valve 23 in line 95 8 connecting the fractionating and the stripping columns so as to keep a constant liquid level in the latter. Such liquid level controlling devices are well known in the art and do not require further description.

By placing the rate of flow controller after 100

the stripping column according to the present invention and especially by placing it after the cooler, as in the preferred form of the invention, inaccuracies of the rate of flow controller due to vaporization in the liquid flow to be controlled are avoided and an accurate control of the side streams becomes possible. The amount of open steam admitted to the stripping column can be easily controlled inasmuch as it is satisfactory to regulate the steam valve by hand as long as the pressure of the superheated steam supply is kept constant. If desired a rate of flow controller may also be inserted in the steam line, or in the case of a very light side stream closed steam coils may be used in column 6 for stripping.

Instead of returning the stripping agent and the light ends to the fractionating column by line 9, this line may be connected by a balance line 24 to the vapor line 3 as shown in dotted line. Since the amount of liquid vaporized in the stripping column is small in comparison to the total amount of liquid passing through the same column it is still possible in this case to maintain steady reflux conditions in the fractionating column 1 by controlling the amount of side stream removed from the system with a rate of flow controller 12 placed behind the cooler 11.

As an example of fractionation carried out according to this invention, a Colombian lubricating distillate was heated in a pipe still and fractionated into an overhead product consisting of gas oil, a bottoms of fuel oil quality and 3 lubricating cuts taken off the tower as side streams. Rate of flow controllers 12, 12', 12'' were placed into the side streams after the coolers 11, 11', 11'' as shown on the figure and the stripping columns 6 were balanced against the vapor line 3 by means of lines 24, 24', 24''. The greater part of the first side stream was returned as reflux to the same three plates in the fractionating column, from which it was taken out. Similarly a large amount of gas oil was returned as reflux to the top plate. The principal data of the operation are given in the following:

50

Table

	Amount	Viscosity Saybolt	Gravity
55			Degrees A.P.I.
Feed.....	Gals/hr		
8,750	650 sec. @ 100° F		22
Overhead.....	250	70 sec. @ 100° F	27.1
1st side stream.....	3,180	180 sec. @ 100° F	25
2nd side stream.....	3,380	925 sec. @ 100° F	21
3rd side stream.....	1,750	140 sec. @ 210° F	18
Bottoms.....	210	.....	16
Reflux (gas oil).....	3,000	70 sec. @ 100° F	27.1
Reflux 1st side stream.....	4,100	180 sec. @ 100° F	25

Although the invention has been described with special reference to the case when the side stream is removed from the fractionating tower through a stripping

column, it will be understood that the latter may be replaced by any receptacle adapted to contain a column of the liquid product removed from the system. The stripping of the side stream from the light ends by means of a stripping fluid such as steam is therefore not an essential part of the invention but the two constitute an advantageous combination.

Having thus described my invention and the method of carrying it out, what I claim is:

1. In a fractionating system, a fractionating tower, means for taking off liquid product from an intermediary portion of the tower, means for stripping said liquid from light ends, a line in connection with said stripping means to remove at least part of the stripped liquid from the system, a rate of flow control device in said line to regulate the amount of stripped liquid removed from the system, and a liquid level control on the stripping column to regulate the amount of liquid taken out of the fractionating tower.

2. Apparatus according to claim 1 in which a cooler is provided between the stripping means and the rate of flow control device.

3. Apparatus according to claim 1 in which the stripping means consists of a column and a line is provided to connect the upper part of the stripping column to the fractionating column.

4. In a fractionating system, a fractionating tower, means for taking off liquid product from an intermediary portion of the tower, a container connected with said means and adapted to hold a column of the liquid product, a liquid discharge line connected with the container, a rate of flow control device in said line to regulate the amount of liquid removed from the system, and a liquid level control on the container to regulate the amount of liquid taken out of the fractionating tower.

PAUL E. KUHL.
